UNITED STATES PATENT OFFICE.

JULIUS HENRY STEAN, OF WORCESTER, MASSACHUSETTS.

PHOTOGRAPHIC-PRINTING DEVICE.

1,281,092.

Specification of Letters Patent.

Patented Oct. 8, 1918.

Application filed November 7, 1917. Serial No. 200,834.

To all whom it may concern:

Be it known that I, JULIUS H. STEAN, a citizen of the United States, residing at Worcester, in the county of Worcester and 5 State of Massachusetts, have invented certain new and useful Improvements in Photographic-Printing Devices, of which the following is a specification.

This invention relates to printing devices, 10 and more particularly to a foldable printing device specially adapted for use in connection with the printing of photographs and for similar purposes.

One of the main objects of the invention 15 is to provide a device of the character stated which may be folded so as to occupy but very little space being well adapted for use by travelers and persons moving from place to place. A further object is to provide a 20 device having white and red lights adapted to be connected to an electric circuit, means being provided for automatically controlling the circuit of the different lights so as to illuminate the white lights when the device is closed, and break the circuit of the 25 white lights and illuminate the red light when the device is open thus permitting it to be used as a dark lantern. A further object is to provide a device having a base and 30 a foldable body mounted thereon, this base and body comprising a light casing, the ends and sides of the body being foldable into the base so as to be contained thereby. A further object is to provide a printing 35 frame carried by the foldable body and hingedly secured thereto so as to fold into the base, this frame having a cover hingedly secured thereto. A still further object is to provide means controlled by the cover of 40 the frame for automatically controlling the light circuits. Further objects will appear from the detailed description:

In the drawings:

Figure 1 is a side view of a printing device constructed in accordance with my invention in folded condition;

Fig. 2 is an end view of the same;

Fig. 3 is a diagram of the light connections;

Fig. 4 is a view similar to Fig. 2 with the device extended;

Fig. 5 is a top plan view of the device folded with the cover for the printing frame raised;

Fig. 6 is a horizontal sectional view taken

in a plane coincident with the upper edge of the base;

Fig. 7 is a longitudinal vertical section taken adjacent one side of the device;

Fig. 8 is a detail of the switch for controlling the circuit of the red light;

Fig. 9 is a detail of the means for controlling the circuit of the white lights and securing the cover in closed position.

The device is provided with a box-like 65 base 1 which is cut away at each end to provide a recess 2. At each end of the base 1 is mounted a foldable member composed of the two hingedly connected sections 3 and 4, these sections being secured together at their 70 adjacent edges by the hinges 5 which are mounted to permit members 3 and 4 to fold inwardly and downwardly. Member 3 is hingedly secured, at its lower edge, to the upper edge of the end of base 1 by hinges 6, 75 these hinges being so disposed as to permit member 3 to fold downwardly and inwardly into the base 1. The members 3 and 4 correspond in length to the recess 2 and are of such thickness that, when folded together, 80 the upper surface of member 4 will be flush with the upper edge of base 1, these members being thus contained within the base, as in Fig. 2 of the drawings.

A printing frame 7 is hingedly secured at 85 its ends to the upper edges of sections 4 by means of hinges 8. These hinges are so mounted as to permit sections 4 to fold inward and upward at the same time that sections 3 fold inward and downward, so as to 90 bring these two sections into parallelism with each other. Frame 7 is provided with an inner rabbet 9 which provides an inner peripheral shoulder 10. This shoulder is adapted to support a plate of glass or other 95 suitable transparent medium upon which may be placed the film and the sensitized paper for printing purposes. The members 3 and 4 constitute the ends of the light casing. One side of this case is closed by a 100 covering 11 of red fabric, the other side being closed by a covering 12 of black fabric, these coverings being secured to the sides of the end members composed of sections 3 and 4 and co-operating therewith and with base 1, to the inner faces of the sides of which the lower portions of these coverings are also secured, to provide a light casing which is entirely closed except at its upper end. The fabric side walls 11 and 12 of this cas- 110

ing being flexible, and the ends being foldable, the body of the casing may be readily folded so as to be positioned within the base 1.

5 Mounted within base 1 and adjacent each corner thereof, is secured a wire spring 13 provided with one or more coils and having its upper arm pressing against the inner face of end section 3. These springs act to 10 normally force the end sections 3 upward and outward thus extending the body portion of the light casing. An eye 14 is secured in member 3 and projects inwardly from the inner face thereof. This eye is adapted to 15 receive a locking finger 15 formed at the upper end of a rectangular or L-shaped catch 16 carried by a push button 17 slideable through the end of base 1. A tension spring 18 is mounted about the horizontal 20 arm of member 16 having its inner end secured thereto and its outer end secured to the end of the base. This tension spring acts to normally hold member 16 outward. When the body of the light casing is in 25 folded condition, eye 14 is in such position as to be engaged by lock finger 15 thus securing end sections 3 in lowered position and maintaining the body of the light casing folded within the base 1. By pressing the 30 push buttons 17 inwardly the lower end sections 3 will be released and the springs 13 will act to extend or raise the body of the light casing as previously described.

A light socket 19 is secured on the inner 35 face of one end of base 1 at the center thereof. This socket receives a red globe or light 20 mounted therein in the usual manner. At the other end of the base 1 are mounted two sockets 21 and 22 in which are secured the 25 lights 23 and 24, these lights being transparent or "white". A plug member 25 is secured in one end of the base 1. This plug member co-operates with a member 26 provided with a cord 27 to electrically connect 40 member 25 to a source of supply of electrical energy. A plug member 28 similar to member 26 is mounted in the inner end of member 25. A wire 29 has one end connected to one pole of plug member 28, the 45 other end of this wire being connected to one pole of socket 19. The other pole of socket 19 is connected by a lead 30 to the lower leaf of one of the hinges 6 at the end of the base on which plug 19 is secured. The 50 upper leaf of this hinge is connected by a strip 31 of copper to the lower leaf of hinge 5, the upper leaf of this latter hinge being connected by a strip 32 of copper to one of the hinges 8. The upper leaf of this 55 hinge is electrically connected by screws 33 to the inner leaf 37 of one of the hinges 34 which hingedly secure one end of cover 35 for the printing frame 7 to one end of the frame, the screws 33 being passed through 60 the end of frame 7 and through the super-

posed leaves of hinges 8 and 34. A copper strip 36 is secured at one end to leaf 37 of hinge 34, this strip being mounted on the upper face of the end bar 38 of frame 7. The inner end of strip 36 is bent up to form 70 a contact member 39 which projects above one end of a vertical groove 40 formed at the center of bar 38. A strip 41 similar to strip 36 is mounted on end bar 38 and is provided with a contact member 42 which projects 75 above the other end of groove 40, the outer end of this latter strip being electrically connected to lower leaf 37^a of the other hinge 34. A contact plate 43 is mounted in groove 40 and is provided at its longitudinal center with a pin 44 secured to the same. The ends of this plate are bent up to form 80 contact members adapted to engage the members 39 and 42 when the plate is raised so as to electrically connect strips 36 and 41. 85 A coil expansion spring 45 is mounted about the pin 44 beneath plate 43. This spring acts to normally hold the plate in raised position. The pin 44 is of such length that, when the cover 35 is in lowered or closed 90 position, it will engage the pin so as to force the plate 43 downward out of contact with members 39 and 42, as in Fig. 8 of the drawings. When the cover is raised, pin 44 will be released and the plate will be raised so 95 as to establish electrical connection between strips 36 and 41. The lower leaf 37^a of the other hinge 34 is electrically connected to the other hinge 8 by screws 33^a, and this other leaf 8 is connected by a strip 46 to the upper 100 leaf of the other hinge 5 the lower leaf of which is connected by a strip 47 to the upper leaf of the other hinge 6. The lower leaf of this latter hinge is connected by a wire 48 to the lower leaf of the corresponding hinge 105 6 at the other end of the casing, which lower leaf is connected by a lead 49 to the other pole of socket member 28. By this arrangement, the red light 20 is connected in series 110 with the circuit so as to be illuminated when the cover 35 for the printing frame 7 is raised. When this cover is lowered, the circuit of light 20 will be automatically broken in the manner previously described.

At the other end of the casing from light 115 20, one of the hinges 6 is connected by a copper strip 31^a to the lower leaf of hinge 5 the upper leaf of which is connected by a copper strip 32^a to hinge 8. This hinge is 120 electrically connected to a copper strip 50 secured on the upper face of end bar 38^a of frame 7. This end bar is provided, in its outer face, with a vertical groove 51, and the inner end portion of strip 50 is turned downwardly into this groove to provide a 125 contact and gripping member 52. A strip 53 similar to strip 50 is secured to bar 38^a at the other side of groove 51 and has its inner end portion turned downwardly into this groove to provide a contact and grip- 130

ping member 52^a corresponding to member 52. The outer end of strip 53 is electrically connected to the other hinge 8 in the same manner as strip 50 is connected to its hinge, 5 and this other hinge 8 is connected to the upper end of the other leaf of the other hinge 5 by a strip corresponding to strip 32^a, the lower leaf of this other hinge 5 being connected by a strip 31^b to the other hinge 6 to the lower leaf of which are connected the wire 48 and lead 49. A lead 54 is connected to the lower leaf of hinge 6 adjacent socket 21 and to one pole of this socket, a lead 55 being connected to the same pole of 10 socket 21 and to one pole of socket 22. A lead 56 is connected to the other pole of socket 22 and to the other pole of socket 21, this lead then being continued to form a supplemental lead 56^a the other end of which is 15 connected to the same pole of socket member 28 as lead 29. Cover 35 is provided at the center of its free or front edge with a plate 54 provided with a depending lug 55. This lug is of such size as to fit 20 snugly between the members 52 and 52^a of strips 50 and 53, respectively, so as to be tightly gripped thereby frictionally. The lug 55 may be made of brass or any other suitable electric-conducting material. When 25 the cover 35 is in closed position, the lug 55 serves to electrically connect strips 50 and 53, the members 52 and 52^a of these strips also acting to releasably secure the cover in closed position.

30 When the cover is closed, the circuit of the red light 20 is broken, and the circuit of the white lights 23 and 24 is closed. When this takes place, the current will flow from the positive pole of socket member 28 to lead 54, 35 to one pole of socket member 21 through lead 54, where the current will divide, one part of the current flowing through lamp 23, and lead 56^a to the other pole of socket member 28, the other part of this current flowing 40 through lead 55 to one pole of socket 22, through light 24 to the other pole of this socket, through lead 56, and lead 56^a to the negative pole of socket member 28. By this 45 arrangement, the lights 23 and 24 are connected in multiple thus insuring a uniform distribution of light during the printing operation. A metallic plate 57 is secured to the inner face of the bottom 1^a of base 1. This 50 plate is highly polished to provide a reflector for directing the light rays upward against the under face of the transparent supporting medium carried by printing frame 7.

55 In using this device, the cover 35 is raised 60 thus automatically turning on or illuminating the red light 20. The film and the sensitized paper may then be properly placed on the glass mounted in the frame 7 for supporting the same. Due to the fact that the red 65 light 20 is illuminated there is no danger of

injury to the sensitized paper during this operation, which may therefore be performed at leisure thus insuring accuracy in placing of the film on the paper. After this has been done, the cover 35 is then lowered thus automatically turning off the red light and illuminating the white lights 23 and 24 so as to reproduce the image of the film on the paper. When the printing operation is completed, the cover 35 may be raised thus shutting off 70 the white lights and again turning on the red lights. In the event that the printing operation is not completed, the reproduction may be examined after which the cover may again be lowered and the printing operation 75 completed. When the reproduction is removed from the printing frame, the red light will be turned on, thus providing a red or dark lantern for use in the subsequent washing of the reproduction. 80

85 A pane of glass 58 is secured in one of the end sections 4 for observation purposes. Due to the fact that the side cover 11 is made from red fabric, the reproduction being printed may be readily examined through 90 the glass 58 by natural light, the red glow caused by cover 11 being sufficient to prevent injury to the sensitized paper from the natural light rays.

95 This device is comparatively simple and is well adapted for use by travelers as it may be folded so as to occupy but very little space. Also, in addition to providing means for printing the pictures, it is well adapted for use as a red or dark lantern in the subsequent washing operation of the reproduction. 100

105 What I claim is:

1. In photographic printing devices, a light casing comprising a box-like base and a body portion hingedly connected thereto at its ends, said body having foldable ends and sides and being adapted to fit within the upper portion of the base when in folded condition, a printing frame carried by the body of the casing at the upper end thereof and hingedly secured at its ends to the ends of the casing, a cover for said frame, said base being adapted to support and contain electric lights mounted within the same and means for closing the circuit of certain of said lights and breaking the circuit of the other lights when the cover is raised, and for closing the circuit of said other lights and breaking the circuit of the first mentioned lights when the cover is lowered said means being also adapted to releasably secure the cover in closed position. 110

115 2. In photographic printing devices, a light casing comprising a box-like base and a body portion having flexible sides and foldable ends each composed of two hingedly connected sections secured to the ends of said base so as to be foldable downwardly and inwardly into the upper portion of the 120 125

130

same, a printing frame carried by the body at the top thereof and having its ends hingedly secured to the ends of the body of said light casing, and a cover hingedly secured at one end to said printing frame.

3. In photographic printing devices, a light casing comprising a box-like base adapted to support lights mounted within the same and a body portion having flexible sides and foldable ends each composed of two hingedly connected sections secured to the ends of said base so as to be foldable downwardly and inwardly into the upper portion of the same into substantially horizontal position, a printing frame carried by the body at the top thereof and having its ends hingedly secured to the ends of the body of said light casing, and a cover hingedly secured at one end to said printing frame.

4. In photographic printing devices, a light casing comprising a box-like base adapted to support lights mounted within the same and a body portion having flexible sides and foldable ends each composed of two hingedly connected sections secured to the ends of said base so as to be foldable downwardly and inwardly into the upper portion of the same into substantially horizontal position, a printing frame carried by the body at the top thereof and having its ends hingedly secured to the ends of the body of said light casing, means for normally holding the ends of said body portion in extended position, and means for releasably securing said ends of the body in lowered position so as to extend inwardly above the base in spaced parallel relation to the bottom of the same.

5. In photographic printing devices, a

light casing comprising a box-like base and a body portion having flexible sides and foldable ends each composed of two hingedly connected sections secured to the ends of said base so as to be foldable downwardly and inwardly into the upper portion of the same, a printing frame carried by the body at the top thereof and having its ends hingedly secured to the ends of the body of said casing, means for normally holding the ends of said body extended, and means for releasably securing said ends in folded position so as to extend in spaced parallel relation to the bottom of said base, said securing means being operable exteriorly of the casing so as to release the ends and to permit said body to be extended.

6. In photographic printing devices, a light casing comprising a box-like base and a body portion having flexible sides and foldable ends hingedly secured to the ends of said base so as to be foldable downwardly and inwardly into the upper portion of the same into substantially horizontal position, a printing frame carried by the body at the upper end thereof and having its ends hingedly secured at one end to one end of said printing frame, said cover serving to close the printing frame when in lowered position, and means for releasably securing the ends of the body of the casing in lowered position extending in parallel spaced relation to the bottom of said base.

In testimony whereof I affix my signature in presence of two witnesses.

JULIUS HENRY STEAN.
